WALDEMAR KOPS, OF NEW YORK, N. Y., ASSIGNEE TO KOPS BROS., OF NEW YORK,
N. Y., A FIRM.

ELASTIC FABRIC.

1,080,284.

Specification of Letters Patent.

Patented Dec. 2, 1913.

Application filed September 27, 1911. Serial No. 651,551.

To all whom it may concern:

Be it known that I, WALDEMAR KOPS, a citizen of the United States, residing at the borough of Manhattan, in the city, county, 5 and State of New York, have invented an Improvement in Elastic Fabrics, of which the following is a specification.

My invention relates to a length or strip 10 of elastic fabric or webbing made inelastic in predetermined sections otherwise than in a process of weaving so as to provide sewing sections by which the elastic fabric is connected to a garment, corset, or other article, and in which these inelastic sections 15 come between the sewing sections and sections under tension whereby any elastic strands cut in the sewing sections are unaffected in the inelastic or anchored sections, therefore not affecting the strands of the 20 elastic section under tension.

In carrying out my invention I take a strip or length of elastic fabric or webbing of usual character and at predetermined intervals produce inelastic sections by saturating 25 the fabric with a foreign substance in liquid form. This foreign substance is preferably an adhesive—unaffected by moisture—which is absorbed by the warp and weft threads of the fabric, filling the interstices between the threads and surrounding 30 the rubber strands and is therefore incorporated with the fabric. When dried this material produces more or less of a rigid condition of the fabric at such sections, 35 whereby the elastic strands are anchored in sections coming between the sewing sections and the elastic parts, and the service or life of the elastic parts is unaffected by the sewed connection to a garment or sup- 40 port.

In the drawing Figure 1 is a plan representing a section of fabric or webbing made according to my invention. Fig. 2 shows a length of webbing treated to produce predetermined inelastic sections.

a represents the elastic section or sections, *b* the inelastic section or sections and *c* the sewing section or sections. The parts *a* are elastic fabric or webbing of any suitable 50 character width or length. The sewing section or sections *c* are also of elastic fabric or webbing of any desired width or length. The inelastic section or sections are of the same character primarily considered, but

are produced in the elastic fabric or webbing 55 of usual character, by treating such parts or sections by saturating the same with a foreign substance in liquid form. This foreign substance in liquid form is absorbed by the warp and weft threads, fills all the interstices between the threads and at the same time surrounds the rubber strands running between the warp and weft threads. This foreign substance in liquid form must be of such a character as to dry and become hard, 60 at least to an appreciable extent, and when in this condition the warp and weft threads are substantially glued or held together and the coating of the foreign substance in liquid form upon the surface of the elastic 70 strands causes same to adhere to the warp or weft threads and to be firmly secured, held, or in other words, locked in the fabric. This foreign substance in liquid form is preferably an adhesive, unaffected by moisture. I have experimented with a number 75 of substances capable of being absorbed by the warp and weft threads and of performing the desired function. Some of these substances dry quicker than others. Some 80 of them become harder when dry than others, but any substance in the form of a gum taken up by liquid substance capable of drying and more or less evaporating, will probably perform the desired office or function. 85

I have, among other things, employed glycerin and glycerin with a small proportion of water glass, and some forms of varnish and also heavy quick-drying oils with a pigment. It is, of course, to be understood 90 that it is not desirable to employ a material which when bent will crack or break or be frangible in any sense of the word. These inelastic sections thus produced come between the length of fabric or webbing to 95 which tension in use is to be applied and—on the other side—the sewing sections which are comparatively short.

It is quite apparent that when the fabric or webbing is attached to a corset, garment 100 or other support by sewing the sewing sections thereto, that if the rubber strands are cut, it can make no possible difference, for the reason that the fabric or warp and weft threads of the sewing section are sufficient 105 to sew the material in place and hold it, and that if these threads are cut such condition does not affect the elastic strands in the in-

elastic section, also does not affect the elastic strands in the sections to be put under tension beyond the inelastic section.

The elastic section or sections may be of any length. The inelastic and sewing sections should be of a width or length sufficient only to perform the functions provided therefor. The elastic fabric or webbing of my invention may be made in substantial endless lengths to be cut up and when cut up each part comprises an elastic section and sewing section and an intermediate inelastic section.

The foreign substance in liquid form or liquid adhesive to be dried, is preferably of such character as to be unaffected by moisture or perspiration, and it is also advantageously colorless so as not to change the color of the fabric.

20 The broken lines $\times \times$ Fig. 1 indicate the places where the fabric is to be severed.

I claim as my invention:

1. An elastic fabric or webbing having spaced elastic sections or parts which come at the respective ends of the webbing, and one of which is adapted to be employed as a sewing section, or section to be sewed or attached to a garment, and an intermediate section made inelastic by a dry adhesive in-

25 corporated in the fabric or webbing, whereby the elastic warps are held or anchored in the intermediate section and the tension applied to the other elastic section is not influenced by the condition of the elastic

30 warps in the section that is attached in the garment.

2. An elastic fabric or webbing having

spaced elastic sections or parts which come at the respective ends of the webbing, one of which is short and the other of which is long, and the short one of which is adapted to be employed as a sewing section or section to be sewed or attached to a garment, and an intermediate section made inelastic by a dry adhesive incorporated in the fabric 45 or webbing, whereby the elastic warps are held or anchored in the intermediate section and the tension applied to the other elastic section is not influenced by the condition of the elastic warps in the section 50 that is attached in the garment.

3. A length of elastic fabric or webbing treated at predetermined intervals and for a predetermined area with a foreign substance in liquid form which fills the interstices surrounding the elastic strands and is absorbed and surrounds the warp and weft threads and when dry locks the elastic strands in place and so forms the inelastic section, and said length of elastic webbing 60 adapted to be severed at predetermined places to form varying lengths of elastic fabric, in which there are elastic sections, at each side of the inelastic section formed as described, and one of which elastic sections 65 is adapted for attachment as a sewing section to a garment.

Signed by me this 22nd day of September 1911.

WALDEMAR KOPS.
